2,240,596

ILLUMINATED SCREW DRIVER

John V. White and Edward J. Ritter, Niles, Ohio;
said Ritter assignor to said White

Application July 25, 1939, Serial No. 286,351

2 Claims. (Cl. 240—6.46)

This invention relates to a screw driver and, more particularly, to a screw driver provided with illuminating means situated in the handle portion thereof.

The principal object of this invention is the provision of an illuminated screw driver, the various parts of which are inexpensive in manufacture and simple in construction.

A further object of this invention is the provision of an illuminated screw driver, the handle portion of which is corrugated so as to provide a better gripping surface and at the same time to provide for a smaller inner diameter suitable for holding a standard size battery in proper position.

A still further object of the invention is the provision of an illuminated screw driver which may be readily disassembled so that the illumination means may be inspected and replaced when necessary.

A still further object of the invention is the provision of an illuminated screw driver adapted to use a prefocused bulb and formed so that the light rays reach the tip of the screw driver with a minimum of shadow.

The illuminated screw driver shown and described herein has been designed to form an inexpensive yet practical illuminated tool that may be conveniently used for tasks wherein the use of an illuminated tool is indicated. The screw driver is formed of a few easily fabricated parts thus serving to make its manufacturing costs very low and permit it to be distributed to the public at very low cost in comparison with other tools of this type.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention is illustrated in the accompanying drawing, wherein:

Figure 1 is a cross-sectional elevation of the illuminated screw driver.

Figure 2 is a cross-sectional view taken on lines 50 2—2 of Figure 1.

Figure 3 is a detail view of the socket portion of the illuminated screw driver shown in Figure 1.

Figure 4 is a detail view, with parts broken away, showing a shank and reinforcing ring por-

tion of the illuminated screw driver shown in Figure 1.

By referring to the drawing and Figure 1 in particular, it will be seen that the illuminated screw driver comprises a tubular housing 1 which is provided with a plurality of corrugations, the inner surface of which form axially extending ridges 2, which serve to form a smaller inner diameter suitable to receive a standard flashlight battery 4.

Still referring to Figure 1, it will be seen that a reinforcing ring 5 has been positioned within the upper end of the tubular housing 1 and that a shank 6 has been affixed to this reinforcing ring 5 (see Figure 4) preferably by spot welding, the shank portion 6 extending downwardly between a pair of the corrugations where it is preferably spot welded to the tubular housing 1. The shank 6 extends outwardly from the tubular housing 1 and has been shaped so that its outermost end 7 is approximately on an axial center line of the said tubular housing. This outermost end 7 of the shank 6 has a conventional tip 8 formed thereon.

By referring to Figures 1 and 3, it will be seen that a socket 9 having a threaded opening 10 therein is suitable for receiving a bulb which is positioned within the tubular housing just below the reinforcing ring 5. This socket 9 is held in position by means of a coil spring 12 which in turn rests against the battery 4 and establishes a definite distance between the socket 9 and the battery 4 so that the bulb may be turned on or off by screwing it in or out of the socket 9 thus making or breaking its contact with the upper terminal of the battery 4. In order that this assembly of parts may be held in operating position, a flanged cap 13 is provided at the lower end of the tubular housing 1. It is so formed that a plurality of crimped flanges 14 thereon slidably engage the inner surface of the tubular housing 1 and engage crimped portions 15 therein. It is obvious that the flanged cap 13 must be formed to correspond with the inner shape of the tubular housing so as to provide for the clearance of the corrugated sections 2. It will be seen that portions of the cap 13 rest against the bottom ends of the corrugations 2 so that any pressure brought against the cap is carried on the housing 1. The center of this flanged cap 13 is preferably bowed so as to provide electrical contact with the bottom of the battery 4.

What we claim is:

1. An illuminated screw driver comprising a handle formed of a section of corrugated tubular

material, a metallic shank rigidly secured in the forward end of the handle at one side thereof by means of a reinforcing ring affixed thereto and positioned within the forward end of the said handle portion, the inner end of the said shank extending inwardly between a pair of the said corrugations, a bulb and socket positioned within the said forward end of the said handle and retained there by the said reinforcing ring and a battery positioned within the said handle adjacent the said bulb, a coil spring positioned between the battery and the said socket together with a cap adapted to close the other end of the said handle.

2. An illuminated screw driver comprising a 15 handle formed of a section of tubular material

provided with a plurality of axially extending corrugations, a metallic shank rigidly secured in the forward end thereof, at one side thereof, by means of a reinforcing ring affixed thereto and to the inner surface of the said tubular material, the outermost end of the said shank terminating on an axially extending center line in relation to the said handle and shaped into a screw driving blade, a bulb and socket assembly positioned within the forward end of the said handle and retained by means of the said reinforcing ring and a battery positioned therebehind within the said handle together with a cap adapted to close the opposite end of the said handle.

JOHN V. WHITE.
EDWARD J. RITTER.
